[57] ABSTRACT

An elevator control apparatus having a tracing device simulating the movement of an elevator cage at a certain reduced speed ratio, a preceding device detecting a target floor to determine the running mode of the elevator cage, a chain moved synchronously with the movement of the elevator cage at a smaller reduced speed ratio than said tracing means, mark plates provided on the chain at intervals proportional to each floor interval, a detector for detecting the mark plates in order to produce signals according to the positions of the elevator cage, and a pattern generator for generating a deceleration pattern by means of relays excited through the output of the detectors when the elevator cage approaches the target floor detected by the preceding device.

ELEVATOR CONTROL APPARATUS

BACKGROUND OF THE INVENTION

The invention relates to an elevator control apparatus, and particularly to improvements in a landing control apparatus for an elevator cage.

It is necessary for deceleration and stopping control of the elevator cage that the target floor be detected at a predetermined distance before it is reached, and that the elevator cage be decelerated in response to a speed pattern which is generated to decrease the speed thereof according to the distance from the target floor. In high speed elevators (generally high-grade elevators), besides a tracing means moved synchronously with the elevator cage movements at a certain reduced speed ratio, a preceding means is further provided on the tracing means, which is moved at higher speed than the tracing means by a preceding motor. The preceding means always goes ahead of the tracing means more than the necessary distance for deceleration of the elevator cage and detects a call signal, i.e., from the target floor. Apparatus of the above-mentioned type, however, generally are very complex and very expensive.

In low speed elevators, preceding detectors are employed which operate always at a fixed distance ahead of the tracing means in contrast to the preceding means of the high speed elevator. The fixed distance is selected to be equal to the deceleration distance of the elevator cage. It is usual that such a preceding detector is immovably attached on the tracing means so as to operate ahead of the tracing means by a distance determined by the deceleration distance for stopping the elevator.

Further, in order to generate the aforesaid speed pattern, namely the deceleration pattern, the position of the elevator cage has to be detected with high accuracy. For this sort of apparatus, the position detectors for the elevator cage are normally arranged directly in the elevator shaft, or the reduced speed ratio for the tracing means is selected to be a comparatively small value. However, the former system provides a complex installation and difficult adjustment of the position detectors since the detectors are arranged distributively in the elevator shaft. Although, comparing the latter system with the former system, the installation and the adjustment of the position detectors are simplified, the latter system comprises a structure of large size. An example of the control apparatus, such as the latter system, is shown in U.S. Pat. No. 2,960,187. Further, if an effort is made toward decreasing said reduced ratio of movement of the tracing means in order to raise the accuracy of the deceleration pattern, the total size of the control apparatus becomes large.

SUMMARY OF THE INVENTION

A main object of the invention is to provide an elevator control apparatus which generates a deceleration pattern with high accuracy.

Another object of the invention is to construct such an elevator control apparatus in a simple structure and with a small size.

According to an aspect of one embodiment of the invention, the control apparatus simulates the elevator movement with a small reduced ratio of movement by means of a long flexible element.

Other objects and features of this invention will become more apparent from the following detailed description when taken in conjunction with the accompanying drawings and the features of the invention will be particularly pointed out in the appended claims.

BRIEF DESCRIPTION OF THE DRAWINGS

FIG. 1 is a schematic diagram in perspective showing an embodiment of the elevator control apparatus in accordance with the present invention;

FIG. 2 is a detailed diagram showing a part of said embodiment;

FIG. 3 is a schematic diagram of a speed pattern circuit;

FIGS. 4a and 4b, when combined, provide a schematic diagram of an operation control circuit;

FIG. 5 is a schematic diagram of a deceleration command circuit;

FIGS. 6a and 6b are a schematic diagram of a position detector and a diagram for explanation of the operative function thereof, respectively;

FIG. 7 is a schematic diagram showing the operation of an example of the position detecting systems;

FIG. 8 is a schematic diagram showing the operation of another example of the position detecting systems;

FIG. 9 shows an output circuit of the position detecting systems; and

FIG. 10 is a diagram for explanation of a deceleration pattern.

DETAILED DESCRIPTION OF THE PREFERRED EMBODIMENTS

For a good understanding of the invention, reference may be had to FIG. 1, wherein various parts of the preferred embodiment of the present invention are schematically shown.

In this figure, a pulley 2 provided at a frame 1 is driven by a steel tape 3 which has holes thereon in rows and one end of which is attached at an elevator cage (not shown). The rotation of the pulley 2 is transmitted to a sprocket wheel 5 through a reduction gear arrangement 4. A tracing means 6 is fixed to a chain 7 driven by the sprocket wheel 5, so that the tracing means 6 goes up and down along a guide bar 8 in proportion to up-down movement of the elevator cage. For example, the tracing means 6 moves at speed reduced from the elevator cage speed in a ratio of 1/100. A fixture 10 is provided on the tracing means 6 in order to support a group of traveling contacts. On the other hand, a group of fixed contacts is arranged to face the corresponding traveling contacts. Such a structure and its operation will be explained fully in connection with FIGS. 2 and 4.

The post 13 carries a plurality of insulating stands 14 at places on the post 13 corresponding to the respective floors. The other sprocket wheel 15 drives an elongated flexible member 16 at higher speed than the tracing means 6, for example, the deceleration ratio of the flexible member 16 is the ratio 1/10 as compared with the deceleration ratio 1/100 of the tracing means 6. This is the reason why the position detecting accuracy of the elevator cage is increased. In this embodiment, an endless chain which is stretched around within the frame 1 and circulated, is used as the flexible member. Besides the endless chain, members having arbitrary

form, such as a tape, a wire, and the other similar elements, can be used as the flexible member. The endless chain 16 has secured thereto a plurality of magnetic shielding plates 18, each corresponding to a respective floor at intervals proportional to each floor interval. In the side of the frame 1, there is provided a position detector 19 which detects the plate 18. A number of position detectors in the side of the frame 1 and a number of plates on the side of the endless chain 16 constitute a position detecting system of the elevator cage. The position detector 19 produces an output signal to perform a detecting operation when the plate 18 passes through a groove 20 of the position detector 19. Further, there is no limitation in the position detector if the detector is an adequate switch to operate as mentioned above.

FIG. 2 is a detailed diagram showing parts of the fixed contacts on the insulating stands 14 and the traveling contacts on the fixture 10. In this figure, fixed contacts 1FS to 8FS are floor zone segments which detect when the elevator cage enters into the zone of the corresponding floor when the traveling contact G on the fixture 10 moves to contact one of the segments. Fixed contacts 1U1 to 1U8 are floor segments for an upward single floor running. A contact 1FU, which is provided on the fixture 10, is a traveling contact for an upward single floor running. The contact 1FU is provided at a relative position which precedes the contact G by one floor position. When the contact 1FU contacts one of the fixed contacts 1U1 to 1U8, a single floor running relay mentioned below is excited on condition that a call of the floor corresponding to the fixed contact exists during the upward running of the elevator cage. Operation of the single floor running relay means that the running mode of the elevator cage is a single floor running mode. Accordingly, in this case, the elevator cage which starts from a certain floor continues the upward running to stop at the next floor. Fixed contacts 2U1 to 2U8 are floor segments for an upward long floor running. A traveling contact 2FU which contacts the fixed contacts one after another by movement of the tracing means 6, are provided at a relative position further ahead of the traveling contact 1FU by one floor position. When the contact 2FU contacts one of the fixed contacts 2U1 to 2U8, a long floor running relay mentioned below is excited to indicate a long floor running mode as the elevator running mode.

The same control is provided for a downward running of the elevator cage. In the side of the insulating stands 14, there are provided fixed contacts 1D1 to 1D8 for a downward single floor running and fixed contacts 2D1 to 2D8 for a downward long floor running. On the other hand, a traveling contact 1FD, which contacts the fixed contacts 1D1 to 1D8 one after another by movement of the tracing means 6, is attached to the fixture 10 at a relative position ahead of the contact G in the direction of movement of the tracing means 6 by one floor position. In the same manner, there is a traveling contact 2FD for a downward long floor running.

The function and operation of the invention will become more apparent from the explanation of the following drawings. FIG. 3 shows a speed pattern circuit, wherein each relay is defined as follows. Relays 21 to 26 are speed pattern relays. The operation of each of

these relays generates the instruction for movement of the elevator cage at the following speeds: relay 21 - 45 m/min, relay 22 - 60 m/min, relay 23 - 75 m/min, relay 24 - 90 m/min, relay 25 - 105 m/min, and relay 26 - 120 m/min. Relays 22T to 26T are time limit relays which operate contacts thereof at a predetermined time, for example 200 m sec., after a release. Relay 15 is the operation relay, which is excited during the operation of the elevator cage, as described in conjunction with FIGS. 4a and 4b. Relay 1F is the single floor running relay. Relay 2F is the long floor running relay, the function and operation of which is already mentioned in connection with the explanation of FIG. 2 and is shown in FIG. 4a. Relays 21S to 26S are deceleration instructing relays, which are excited one after another according to the position of the elevator cage during deceleration, and are shown in FIG. 5.

Further, the contacts in FIG. 3 are designated by hyphenated numerals besides the symbols of the relays; for example, contacts 21-1 and 21-2 belong to the relay 21, in which the contact 21-1 is a normally closed contact and the contact 21-2 is a normally open contact. All of the contacts in the following figures are designated in a manner similar to that of this figure.

The operation of the circuit above described is as follows. The speed pattern relays 21 to 26 are excited in the sequence of 21, 22, 23, 24, 25 and 26 by the operation of the time limit relays 22T to 26T to generate the acceleration pattern which is a time speed pattern. Now, if the running mode of the elevator cage is the single floor running mode, the relay 1F is excited and the relay 2F is not excited. The contacts 1F-3 and 2F-3, therefore, are opened together to prevent rising of the pattern speed to more than 90 m/min, which is determined by the relay 24. In the case of the long floor running mode, the pattern speed is generated up to 120 m/min, since the relay 26 is excited by closing of the contact 2F-3.

During deceleration, the relays 21S to 26S in FIG. 5 are excited one after another in the sequence of 26S, 25S, 24S, 23S, 22S and 21S according to the position of the elevator cage so that their contacts 26S-1 to 21S-1 are opened in the same sequence. The relays 21 to 26, therefore, are released in the sequence of 26, 25, 24, 23, 22 and 21 to generate the deceleration pattern as shown in FIG. 10. As mentioned up to here, the circuit shown in FIG. 3 is the circuit which generates the acceleration pattern (the time-speed pattern) by the operation of the time relays during acceleration and the deceleration pattern (the distance-speed pattern) by the operation of the deceleration instructing relays according to the positions of the elevator cage during deceleration.

FIG. 4 shows an example of an operation control circuit, wherein the same references are shown heretofore represent corresponding elements as illustrated in the preceding figures. The circuit in FIG. 4 further includes diodes D0, D11 to D14, D21 to D24, . . . and D61 to D64; an upward running instruction relay 61A which generates an upward running instruction for the elevator cage; a downward running instruction relay 62A, which generates a downward running instruction for the elevator cage; contacts C1-1, C1-2 to C6-1, C6-2 which are closed when a destination button switch within the elevator cage is operated; normally open

contacts HU1-1 to HU6-1 which are closed when an upward call on a floor is registered; normally closed contacts HU1-2 to HU6-2 which are opened when an upward call on a floor is registered; normally open contacts HD1-1 to HD6-1 which are closed when a downward call on a floor is registered; normally closed contacts HD1-2 to HD6-2 which are opened when a downward call on a floor is registered; contacts FR1-1 to FR6-1 and FR1-2 to FR6-2 which are opened when the elevator cage is in each floor zone; upward running relay U, which is excited during the upward running of the elevator cage (shown by contacts only); downward running relay D, which is excited during the downward running of the elevator cage (shown by contacts only); and door relay 40, which is excited after securing safety by closing the cage door (shown by contacts only).

The circuit shown in FIG. 4 has the following three functions. Namely, the first function is to determine the running direction of the elevator cage by detecting the relative position between the position of the elevator cage and the floor associated with the call (the target floor); the second function is to determine whether the running mode of the elevator is the single floor running mode or the long floor running mode; and the third function is to detect the target floor.

FIG. 5 is a schematic diagram showing an example of a deceleration instructing circuit, wherein references 21TH to 26TH designate thyristors to which are applied the gate signals which render them conductive one after another during deceleration, and references 21C to 26C are gate electrodes connected to the output terminals of the position detectors. The explanation of the relays 21S to 26S has already been provided in connection with FIG. 3. References of contacts in this figure are employed in the same manner as before.

The gate signals of the thyristers 21TH to 26TH are obtained from the position detecting system. In this case, each position detector in the position detecting system is constructed as shown in FIG. 6a, in which references M1 and M2 designate coils magnetically coupled to each other, and a reference C is an output terminal. When the plate 18 is driven by the endless chain 16 until it passes between the coils M1 and M2, an output as shown in FIG. 6b is obtained at the terminal C since the plate 18 acts as a shield to eliminate the magnetic coupling between the coils M1 and M2. A number of such position detectors are connected to provide an electric circuit of the position detecting system, as shown in FIG. 9. During deceleration in the upward running direction, a contact U-4 is closed so that the position detectors 26 MU to 21MU operate to produce the outputs one after another, and during deceleration in the downward running direction, a contact D-4 is closed so that the position detectors 26MD to 21MD operate in the same manner.

As a mechanical arrangement of these position detectors, two arrangements are considered. One is shown in FIG. 7, wherein a plurality of plates 18M51 to 18M56 are provided at a place on the endless chain 16 according to each floor and the position detectors 21MD to 26MD for the downward running direction and 21MU to 26MU for the upward running direction are provided corresponding to the plates 18M51 to 18M56. The other is shown in FIG. 8, wherein the plates 18M1 to 18M5 corresponding to each floor are

provided in the interval equal to the interval between floors, and the position detectors 21MD to 26MD for the downward running direction and 21MU to 26MU for the upward running direction are provided in a row. 5 These arrangements may be selected at will since both have advantages and disadvantages.

The operation of the apparatus above described is as follows. The following explanation will be performed for the case where the elevator cage is stopped at the 10 third floor and begins running in response to a call produced on the fifth floor.

When a passenger on the fifth floor registers a call for movement of the elevator in an upward direction, the contact HU5-1 is closed and the contact HU5-2 is opened in FIG. 4b. Then, a circuit of battery (+), 61A, 62A-1, FR6-2, FR6-1, FR5-2, D51, HU5-1, and battery (-) is formed so that the upward running instruction relay 61A is excited. By exciting of the relay 61A, 15 an upward instruction is produced by the other circuit (not shown). The contacts 15-1 (in FIG. 3), 15-2, and U-1 to U-3 are closed thereby. The relay 21 in FIG. 3 is excited by the closing of the contact 15-1 so that the elevator cage begins an upward running movement. At 20 the same time, the relay 21 is excited, the contact 21-1 is opened, and therefore, the relay 22T is cut out from the electric source. After the passing of a predetermined time, the contact 22T-1 is closed to excite the 25 relay 22. Hereinafter, the relays 23, 24, 25, and 26 are excited one after another in the same manner as before, so that the acceleration pattern is generated up to the 30 pattern speed instructed by the relay 26, namely 120 m/min. and the elevator cage is accelerated up to 120 m/min.

On the other hand, as the elevator cage goes up, the traveling contact 2FU goes up, too. When the elevator cage reaches a place at a predetermined distance before the fifth floor level FFL, the contact 2FU comes in contact with the fixed contact 2U5. In FIG. 4a, the relay 2F is excited through the circuit of battery (+), 2F, 24-3, 1F-2, U-1, 2FU, 2U5, HU5-1, and battery (-). The relay 2F is self-held through the circuit of battery (+), 2F, 2F-1, 15-2 and battery (-). By means of the closure of the contact 2F-1, the relay 1F is excited through the circuit of battery (+), 1F, D0, 2F-1, 15-2 and battery (-), so that the relay 1F is also self-held through the circuit of battery (+), 1F, 1F-1, 15-2 and battery (-). The excitation of both relays 1F and 2F is continued until the elevator cage stops to open the contact 15-2. When the relays 1F and 2F are excited, the contacts 1F-4 and 2F-4 in FIG. 5 are closed to complete the preparation for operating a deceleration instructing circuit.

When the elevator cage approaches the fifth floor after continuing the upward running for an adequate time, the plate 18M5 corresponding to the fifth floor faces the position detector 26MU, as shown in FIG. 8. At this time, an output appears on the terminal 26C of the position detector 26MU. The output is applied to the gate of the thyristor 26TH in FIG. 5. The thyristor 26TH conducts to excite the relay 26S. As the elevator cage further approaches the fifth floor, the plate 18M5 faces the position detectors 25MU, 24MU, 23MU, 22MU and 21MU in sequence. As a result, outputs appear on the terminals 25C, 24C, 23C, 22C and 21C in sequence in FIG. 9, and the relays 21S to 25S in FIG. 5

are excited with the sequence of 25S, 24S, 23S, 22S and 21S and self-held. Accordingly, the contacts 26S-1 to 21S-1 are sequentially opened to release the relays 26 to 21 in FIG. 3. The pattern speed is gradually decreased as shown in FIG. 10 in accordance with the sequential release of the relays 26 to 21. In this way, the elevator cage is decelerated to stop at the fifth floor according to the speed pattern produced as mentioned above.

Further, when the distance required for the deceleration amounts to more than two floor intervals, more than two position detectors operate simultaneously. However, if the long floor running relay 2F is excited, the relays, except the relays 26S and 25S, are not excited first in FIG. 5 since they are interlocked by the contacts 26S-3 and 25S-3. In practice, adjacent position detectors, such as 26MU and 25MU, do not operate simultaneously. For example, before the plate 18M5 in FIG. 8 faces the position detector 26MU, the plates 18M4 and 18M3 face the position detectors 24MU and 21MU, respectively. However, since the contacts 25S-3, 26S-3, and 23S-3, 24S-3 in FIG. 5 are opened, the corresponding relays 24S and 21S are not excited.

Next, an explanation will be given for the case wherein the elevator cage on the third floor is operated in response to a call produced on the fourth floor, namely the single floor running mode.

When a passenger on the fourth floor registers a call directing movement of the car in a downward direction, the contact HD4-1 is closed and the contact HD4-2 is opened in FIG. 4. Then, the relay 61A is excited through the circuit of battery (+), 62A-1, FR6-2, FR6-1, FR5-2, FR5-1, D42, HD4-1 and battery (-). An upward instruction is produced by excitation of the relay 61A and at the same time, contacts 15-1 (in FIG. 3), 15-2 and U-1 to U-3 are closed. The relays 21 to 26 are excited in sequence. In the case of the single floor running mode, however, before the relay 24 is excited, the contact 1FU comes in contact with the fixed contact 1U4 owing to the short running distance. The relay 1F is excited through the circuit of battery (+), 1F, 24-2, 40-1, U-2, 1FU, 1U4, HU4-1 and battery (-). The contact 1F-1 is closed so as to be self-held, and the self-holding continues until the time when the elevator cage stops to open the contact 15-2. Accordingly, the relays 25 and 26 in FIG. 3 are not excited so that the elevator cage is not accelerated more than 90 m/min in the single floor running mode. When the elevator cage approaches a predetermined distance before the fourth floor, the plate 18M4 faces the position detector 24MU in FIG. 8. After this, the plate 18M4 faces the position detectors 23MU, 22 MU, and 21MU one after another. The relays 24, 23, 22 and 21 in FIG. 3 are released in sequence to generate the deceleration pattern, as shown in FIG. 10. The elevator cage is decelerated according to the deceleration pattern, and stops at the fourth floor.

The above-mentioned are the explanations for the single floor running mode and the two floor running mode. In the case of running modes exceeding three floors, except increasing of the term or the distance in which the elevator cage runs at the maximum speed of 120 m/min, the acceleration and deceleration pattern are similar to the pattern for the two floor running mode.

Further, the above-mentioned description provides an explanation for the operation of the elevator cage in response to the call produced on each floor. When a passenger operates a destination button switch in the elevator cage, a pair of contacts of the contact pairs C1-1, C1-2 to C6-1, C6-2 are closed. However, these contacts, such as C3-1 and C3-2, are connected with the contacts HD3-1 and HU3-1 in parallel, respectively. The operation after a closure of the contacts C3-1 and C3-2 is equal to the above-mentioned operation in response to the call produced on the floor.

In this embodiment, the endless chain is employed as the flexible member. Various types are provided instead of the endless chain. For example, an adequate wire or tape which is wound up by a reel, may be used. By such types, the space factor becomes much higher than the endless chain type. Such wire or tape can also be used in the endless type. In spite of types, i.e., the endless type or the reel type, if a magnetic wire or tape is employed, the position detecting system is further reduced in size, because the signal corresponding to each floor is magnetically recorded thereon instead of the magnetic shielding plate and magnetic heads are employed as the position detectors.

While we have shown and described several embodiments in accordance with the present invention, it is understood that the same is not limited thereto but is susceptible of numerous changes and modifications as known to a person skilled in the art, and we therefore do not wish to be limited to the details shown and described herein but intend to cover all such changes and modifications as are obvious to one of ordinary skill in the art.

What is claimed is:

1. An elevator control apparatus having first means operatively connected to the elevator cage for tracing the movement of an elevator cage with a certain reduced speed ratio therewith and second means detecting a target floor to determine the running mode of the elevator cage, the improvement comprising an elongated flexible member moved synchronously with the movement of the elevator cage with a smaller reduced speed ratio than said first means, mark means provided on said flexible member at intervals proportional to each floor interval, means for detecting said mark means in order to produce signals according to the positions of the elevator cage, and means for generating a deceleration pattern in response to outputs of said detecting means when the elevator cage approaches the target floor detected by said second means.

2. An elevator control apparatus according to claim 1, wherein said generating means includes means responsive to said second means for generating deceleration patterns having different maximum speeds in accordance with the running mode of the elevator cage detected by said second means.

3. An elevator control apparatus according to claim 1, wherein said elongated flexible member is formed as an endless loop.

4. An elevator control apparatus according to claim 3, wherein said elongated flexible member is wound up by a reel in proportion to the movement of the elevator cage.

5. An elevator control apparatus according to claim 3, wherein said elongated flexible member is an ele-

ment selected from the group consisting of chains, wires and tapes.

6. An elevator control apparatus according to claim 3, wherein said elongated flexible member is an element selected from the group consisting of wires and tapes.

7. An elevator control apparatus according to claim 6, wherein said elongated flexible member is made of magnetic material, and signals are magnetically recorded thereon at intervals proportional to each floor interval to form said mark means, said detecting means being provided as magnetic heads for detecting the recorded portions of said flexible member.

8. In an elevator control apparatus including tracing means translated in coordination with the elevator cage at a certain reduced speed ratio therewith and second means driven by said tracing means for detecting a target floor to determine the running mode of the elevator cage, the improvement comprising position detecting means for detecting the position of said elevator cage with respect to the various floors including an elongated flexible member moved in coordination with the elevator cage with a smaller reduced speed ratio than said tracing means.

9. An elevator control apparatus according to claim 8, wherein said second means includes a first set of stationary contacts spaced in proportion to the intervals between floors and a first movable contact carried by said tracing means at a position ahead of said tracing means by one floor interval, and speed control means

responsive to contact of said first movable contact with one of said first set of stationary contacts receiving a control signal for limiting the maximum speed of said elevator cage.

5 10. An elevator control apparatus according to claim 9, wherein said second means further includes a second set of stationary contacts spaced in proportion to the intervals between floors and a second movable contact carried by said tracing means at a position ahead of said tracing means by two floor intervals, said speed control means being responsive to contact of said second movable contact with one of said second set of stationary contacts receiving a control signal for initiating deceleration of said elevator cage.

15 11. An elevator control apparatus according to claim 10, wherein said elongated flexible member is formed as an endless loop.

20 12. An elevator control apparatus according to claim 11, wherein said elongated flexible member is wound up by a reel in proportion to the movement of the elevator cage.

25 13. An elevator control apparatus according to claim 12, wherein said elongated flexible member is made of magnetic material, and signals are magnetically recorded thereon at intervals proportional to each floor interval to form said mark means, said detecting means being provided as magnetic heads for detecting the recorded portions of said flexible member.
